CLAIM

We claim the ornamental design for a development apparatus for printer, as shown and described.

DESCRIPTION

FIG. 1 is the front perspective view of a development apparatus for printer showing our new design;

FIG. 2 is the front view thereof;

FIG. 3 is the rear view thereof;

FIG. 4 is the left-side view thereof;

FIG. 5 is the right-side view thereof;

FIG. 6 is the top view thereof;

FIG. 7 is the bottom view thereof;

FIG. 8 is the rear perspective view thereof; and,

FIG. 9 is the bottom perspective view thereof.

The broken lines depict portions of the development apparatus for printer that forms no part of the claimed design.
